EMMANUEL LAVALLEE, OF PAWTUCKET, RHODE ISLAND.

SWELL CHECK FOR LOOMS.

1,408,010.

Specification of Letters Patent. Patented Feb. 28, 1922.

Application filed December 9, 1919. Serial No. 343,544.

To all whom it may concern:

Be it known that I, EMMANUEL LAVALLEE, a citizen of the United States, and a resident of Pawtucket, in the county of Providence 5 and State of Rhode Island, have invented certain new and useful Improvements in Swell Checks for Looms, of which the following is a specification.

My invention is an improvement in swell 10 checks for looms, and has for its object to provide a device of the character specified for permitting the comparatively easy entrance of the shuttle into the shuttle box, but for preventing rebound of the shuttle in the 15 box and to lock the shuttle in the box until the next stroke of the picker, wherein the pressure of the check is yieldable, permitting comparatively free passage of the shuttle in one direction, but braking its passage 20 in the other, and wherein the extent of the braking action may be varied.

In the drawings:

Figure 1 is a plan view of the improved check;

25 Figure 2 is a section turned 90 degrees to the right, and Figures 3 and 4 are sections on the lines 2—2, 3—3 and 4—4, respectively, of Figure 1.

In the present embodiment of the invention 30 the shuttle check comprises a body 1 provided with a hub 1' which turns on a vertical binder stud 2', said body being adapted through the medium of the usual protector rod which turns in journals on the 35 under side of the lay-beam to raise or lift the dagger so that the same will normally be raised clear of the frog by a shuttle in either box pressing the corresponding body against a dagger rod finger not shown, but 40 when a shuttle is in neither box, the dagger is down and in the forward movement of the lay will strike said frog and move the same to throw the lever out of its holding notch and stop the loom, all of the 45 above named parts being of the usual construction and operation except as hereinafter described. The body or binder 1 is provided intermediate its ends with a passage 2, through which extends a lug 3 on the supplemental or secondary swell 4. The swell, 50 as shown more particularly in Figure 2, is pivoted to the body by means of this lug 3, a screw bolt 5 being passed through registering openings in the lug and in the body and being engaged by a nut 6 at the opposite 55 face of the body or may consist of a stud

with a head on one end and a screw on the other and threaded in a socket provided therein so as to retain the swell in position. The lug 3 has an extension 7 at one end, 60 through which is threaded a set screw 8, and the free end of this set screw engages the under face of a rabbet 9 at the forward end of the passage 2 to limit the inward or lateral movement or projection of the swell. 65

A lock nut 10 is threaded onto the set screw, for holding it in adjusted position, and the outer end of the swell is normally pressed inward by means of a spring 11. This spring is secured at one end to the body 70 by means of a screw 12 and a machine screw or bolt and nut 13, and the spring extends or is curved over the projecting end of the lug 3 adjacent the pivot 5 thereof and the free end of the spring bears against the lug 75 3 at its free end at its junction with the extension 7. That portion of the inner face of the body 1 toward the outer end thereof forming a swell is covered with a layer 14 of leather or other material having a high 80 co-efficient of friction.

The picker stick indicated at 18 moves in the slot 19 in the shuttle box 15.

Referring to Figure 1, it will be seen that by means of the set screw the swell may be 85 so adjusted that it will exercise just the proper degree of braking action on the shuttle when it is driven into the shuttle box, indicated at 15, to prevent rebound of the 90 shuttle. The swell acts in somewhat the manner of a pawl, permitting the free entrance of the shuttle to the box, but opposing its passage from the box. It will be understood that the improved check forms a portion of the rear wall of the shuttle box as 95 indicated in Figure 1. The front wall of the box is formed by a plate 16, adjustably connected with the box as indicated at 17. The body 1 is pivoted at its outer end to the lay upon the top plate 15 secured thereto, as 100 indicated at 1', 2'. It is also to be understood that the body 1 may be provided or pivoted at the front or rear of the box, according to the particular construction or type of loom employed and that it is limited 105 in its movement during the oscillation of the lay in the usual or any preferred manner as shown in the patents to Mills 756,036, March 29, 1904, Cayten 1,120,026 Dec. 8, 1914, Bailey and Snow 716,514 Dec. 23, 1902; 110 Roper 761,999 June 7, 1904 and Mills 820,662 May 15, 1906.

I claim:

1. In a swell check for looms, a pivoted body, means for causing the body to be yieldingly pressed inward throughout its length, said body having a swell and having a slot near its pivoted end, a supplemental swell having a lug extending through the slot and pivoted near its outer end for movement therein, said supplemental swell being disposed adjacent to the swell of the body and adapted for movement with respect thereto, a spring normally acting to force the inner end of the supplemental swell inwardly, and means for adjusting and limiting the movement of the supplemental swell on its pivot, said body having a rabbeted portion at the outside thereof beyond the inner end of the lug, said lug having an extension disposed in the rabbeted portion, and a set screw engaged through the extensions having means for adjustably locking it in position through the extension and with respect to its projection from the inner face thereof to engage the inner wall of the rabbeted portion whereby to limit the inward movement thereof and the supplemental swell.
2. In a swell check for looms, the combination with the lay including a top plate having a slot for receiving the picker stick, a plate at one side of the slot, a body pivoted at the other side of the slot and held toward the same to engage a shuttle, said body having a swell and having a reduced portion forming a recess at the inner side and a slot horizontally through the same at the inner end of the recess, a supplemental swell having a lug pivoted in the slot, said pivot extending vertically and permitting movement of the lug on a horizontal plane, said swell provided with the lug cooperating with the swell of the body and movable with respect thereto, a spring secured on the outer edge of the body and curved over and acting at its free end upon the free rear end of the lug to normally project the supplemental swell with respect to the body, and means co-acting between the lug and the body to limit the inward movement of the lug and the projection of the supplemental swell.
3. The combination with a loom having a lay plate for receiving the shuttle and a picking mechanism, a checking device comprising a pivoted body carried by the plate, means for causing the pivoted body to be yieldingly pressed inward throughout its length, said body having a swell at its free end and inner face and having a reduced portion forming a recess at the inner side thereof adjacent to the pivot, said body having a slot horizontally through the same at the inner end of the recess, a supplemental swell having a lug pivoted in the slot, a spring secured in the outer edge of the body and curved over and acting at its free end upon the free rear end of the lug to normally project the supplemental swell with respect to the body, and means co-acting between the lug and the body to limit the inward movement of the lug and the projection of the supplemental swell.
4. In a swell check for looms, the combination with a loom; of a shuttle box or top plate of a lay having a slot, a picker stick operating in said slot, said shuttle box having a stationary wall and a cover plate; of a body pivoted at one end upon the plate and forming the opposite wall disposed upon the opposite side of the slot with respect to the first named wall for receiving the shuttle therebetween, said body comprising a swell near the free inner end thereof, and an auxiliary check swell carried by the body and movable independently of and with respect to the swell of said body to supplement the checking action thereof with respect to the shuttle, said auxiliary check swell being adjustably limited in its inward movement.
5. The combination with a shuttle box or top plate of a lay; of a check forming a portion of one wall thereof and comprising a body pivoted at its outer end to the outer end of the box or plate, said body having a horizontal slot in the median plane of the box and body and provided with a swell near the free end thereof, a supplemental swell pivoted in the slot intermediate the ends thereof, a spring normally acting to force the inner end of the body inwardly, and inter-engaging means in connection with the body and swell for limiting the inward movement of said end of the swell with respect to the body, said inter-engaging means comprising an extension lug on the inner end of the swell, the body being rabbeted to receive the extension lug, and a set screw threaded through the extension lug for engaging the wall of the rabbet.
6. In a swell check for looms, a shuttle check, means for causing the shuttle check to be yieldingly pressed inward throughout its entirety, said check having a swell and having a slot near its pivoted end, a supplemental swell having a lug extending through the slot and pivoted near its outer end for movement therein, a spring normally acting to force the inner end of the supplemental swell inwardly, and means for adjustably varying and limiting the inward movement of said supplemental swell on its pivot.
7. In a swell check for looms, a shuttle check, means for causing it to be yieldingly pressed inward throughout its entirety, said check having a swell and having a slot near

its pivoted end, a supplemental swell having a lug extending through the slot and pivoted near its outer end for movement therein, a spring normally acting to force the inner end of the supplemental swell inwardly, and means carried by the inner end of the supplemental swell and cooperating with the shuttle check for adjusting and limiting the inward movement of said supplemental swell

10 on its pivot.

8. In a swell check for looms, a shuttle check comprising an elongated rigid body pivoted eccentrically upon the top plate of a loom lay adjacent to the picker stick slot 15 and shuttle, and having a swell near the free inner end thereof, a supplemental check swell carried by the body adjacent to the

pivoted end thereof and having its swell disposed for movement within and beyond the plane of the engaging portion or swell of 20 the body, spring means for projecting the supplemental swell, rigid means for limiting the projection of the supplemental swell beyond the engaging edge of the body and independently of the pivotal movement of 25 the latter, and rigid means for positively regulating the degree of projection of said supplemental swell with respect to the body, independently of the spring means, said means coacting between the inner end of 30 the supplemental swell and the adjacent portion of the shuttle check body.

EMMANUEL LAVALLEE.
